FOLDING CHAIR

John J. Croft, Siler City, N. C., assignor to High Point Bending & Chair Co., Siler City, N. C., a corporation of North Carolina

Application May 18, 1936, Serial No. 80,459

1 Claim. (Cl. 155—141)

This invention relates to folding chairs, and the primary object thereof is to provide simplified means for securely and positively retaining the chair both in operative and folded positions, 5 against accidental movement.

A further object of the invention is to provide a chair of this type which can be economically manufactured; which embodies a minimum of parts, and one wherein the folding and unfolding operations may be easily and quickly performed.

The invention has still further and other objects which will be later set forth and manifested in the course of the following description.

15 In the drawings:

Fig. 1 is a vertical sectional view of the invention, in operative position;

Fig. 2 is a section on line 2—2 of Fig. 1;

Fig. 3 is a section on line 3—3 of Fig. 1;

20 Fig. 4 is a front elevation of the invention in folded position;

Fig. 5 is a section on line 5—5 of Fig. 4; and

Fig. 6 is a detail view of the guide and wear plate.

25 In proceeding in accordance with the present invention, a back 1 is provided having legs 2; a seat 3 being pivoted to the back by means of brackets 4. Front legs 5 are pivotally connected to the seat by means of brackets 6. The 30 seat is provided on its under side face with side rails or members 7, which latter have longitudinal grooves 8 formed on their confronting or inner side faces. The grooves 8 have right angular end portions 9 which extend toward the 35 seat.

Combined guide and wear plates 10 are secured to the inner side faces of the rails 7, for example by means of screws 11. As depicted in Figs. 1 and 3, the lower side edges of the 40 plates 10 aline or register with the upper side walls of the grooves 8, or otherwise stated, register with the side walls of the grooves adjacent the seat. The plates 10 are likewise formed with right angular recesses 12, adjacent their 45 end parts, which register with the right angular end portions 9 of the grooves 8.

Referring particularly to Fig. 3 it will be seen that a rod 13 is disposed transversely beneath the seat and has rollers 14 mounted on its ends 50 which are receivable in the grooves 8 and the recesses 9 and 12, the rollers engaging against the undersides of the plates 10. Short braces 15 are pivoted at 16 at their outer ends to the front legs 5 and at their inner ends pivoted 55 to the rod 13. Rear braces 17 are pivoted at 18

to the rear legs 2 and have their inner ends offset and pivoted to the rod 13. For the purpose of holding the braces 15 and 17 against movement inwardly of the rod 13, means, for example, the sleeve 19 is mounted on the rod 5 13 and has its ends abutting the braces 17. It will be noted that the rollers 14 are disposed closely adjacent to the braces 15, so that same as well as the braces 17 are held against movement longitudinally and outwardly of the rod 13. 10

Referring now to Fig. 1 it will be seen that when the chair is in operative position the rollers 14 are engaged in the front recesses 12 of the plate 10, which recesses constitute keepers for the rollers, and in such position of the parts it 15 will be apparent that the chair is effectively and rigidly held in operative position. In order to fold the chair it is merely necessary to grasp the back 1 in one hand and then move the seat 3 with the other hand upwardly toward the back, 20 whereupon the two rollers 14 will ride against the lower side edges of the plates 10 until they reach the registering recesses 9 and 12, whereupon the rollers will enter the latter as shown in Fig. 5 thus positively holding the chair in 25 folded position and against accidental opening.

The plates 10 function to provide an edge 30 against which the rollers ride, thereby preventing wear on the walls of the recesses 8, and further act to assume all strains and stresses 35 to which the rollers 14 may be subjected due to the weight of the occupant of the chair. By virtue of the grooves 8 being formed in the depending portions 7 at the sides of the seat it will be seen that a greater bearing is afforded 40 for the rollers 14, thus adding to the stability of the chair when in operative position. The plates, in addition, act to reinforce and strengthen the side rails 7 of the seat and still further act as abutments against which the 45 braces 15 may engage to thus prevent the latter from engaging and consequently wearing away the wood or other non-metallic material of which the depending members 7 are generally formed.

It is particularly to be noted that the instant 45 invention involves a minimum of parts that are compactly assembled, and can be easily operated, and by virtue of the location of the braces 15 and 17 closely adjacent to the front and rear legs a more stabilized structure is provided and one which maintains the chair at a maximum of rigidity when in its operative position.

Obviously, the rollers may be dispensed with, if desired, but are preferably used to constitute 50 55

a part of the rod 13 in order to facilitate sliding movement of the latter.

What is claimed is:

In a folding chair or like device, a back having 5 legs, a seat pivoted to the back and having depending members at its sides, each formed with a longitudinal groove having substantially right angular end parts, which latter extend toward the seat, front legs pivoted to the members, a 10 rod extending transversely of the seat and having rollers on its ends slidable in the grooves and receivable in the end parts of the latter, a guide plate secured on the inside of each of the depending members and having downwardly open- 15 ing recesses forming keepers to receive the rollers at the ends of the rod, which recesses register

with the said end parts of the grooves, said guide plate further having a side edge which registers with the side wall of the groove adjacent the seat, and against which edge the rollers engage, a pair of braces at each end of the rod 5 having inner ends pivoted to the rod and having outer ends pivoted to the rear and front legs respectively, and a sleeve on the rod having ends which engage the inner ends of the adjacent braces and which hold the said inner ends 10 of the adjacent braces against the inner ends of the other braces thereby to hold the latter against the plates and to prevent sliding of the rollers on the rod.

JOHN J. CROFT. 15
